*Primary Examiner—A. Hugo Word**Assistant Examiner—Doris V. Coles**Attorney, Agent, or Firm—Leon Gilden*[57] **CLAIM**

The ornamental design for a body pouch, as shown and described.

DESCRIPTION

FIG. 1 is a front elevational view of the body pouch showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof; and,

FIG. 7 is a perspective view thereof showing the invention attached to a user's arm.

The broken line showing of a body pouch user is for illustrative purposes only and forms no part of the claimed design.
